TORCH

George L. Walker, Jersey City, N. J., assignor to
 Air Reduction Company, Incorporated, New
 York, N. Y., a corporation of New York

Application October 28, 1942, Serial No. 463,579

2 Claims. (CL 158—27.4)

This invention relates to improvements in torches such as are used for oxygen cutting.

One object of the invention is to provide an improved torch for cutting wide kerfs. While it is true that larger oxygen jets cut wider kerfs, it is not economical to use larger jets than are required for the thickness of the work to be cut. For additional width, such as in slot cutting, it is more advantageous to use a row of cutting jets spaced closely enough to produce a single kerf. This invention relates to torches of the type having a row of closely-spaced cutting jet orifices.

In accordance with one feature of the invention the cutting orifices are closer to the surface of the workpiece than are the preheating jet orifices. This relation gives a new result in a multi-cutting jet torch. There seems to be some kind of interaction between the different oxygen jets that prevents them from cutting a kerf with parallel sides when the jets are located in a row and close enough together to cut a single wide kerf in a direction transverse of the row. I have discovered that the closely-spaced oxygen jets do not react upon one another in this way if the orifices from which the jets issue are located close to the surface of the workpiece and the preheating-flame passages are spaced further from the work.

Another object of the invention is to distribute the gas more evenly among a number of different orifices. This object is attained as a result of several features of construction. In accordance with one feature, the torch is provided with two distributing chambers, with connecting passages through which gas from a primary chamber flows into a secondary chamber, in combination with an equal number of metering ports through which the gas flows from the secondary chamber to the jet passages of the torch.

Another feature relates to jet passages spaced along the length of a distributing chamber to which gas is supplied through a conduit that opens through the wall of the chamber on the side opposite the gas passages, those gas passages directly opposite the inlet being of reduced size to counteract the effect of approach velocity. More even flow of gas through the different passages is obtained.

Other objects, features and advantages of the invention will appear or be pointed out as the specification proceeds.

In the accompanying drawing, forming a part hereof:

Fig. 1 is an end view of a cutting tip embodying this invention.

5 Figs. 2 and 3 are sectional views taken on the lines 2—2 and 3—3, respectively, of Fig. 1.

Fig. 4 is a view similar to Fig. 1, but showing a modified form of the invention.

Fig. 5 is a sectional view on the line 5—5 of 10 Fig. 4.

A tip 10 fits into a socket in a torch head 11 and is held in place by a tip nut 12. There is an inlet conduit 13 through which cutting oxygen is supplied to a primary distributing chamber 14.

15 Passages 16 and 17 open through the side of the distributing chamber 14 that is opposite the inlet conduit 13 and at points spaced lengthwise of the chamber. These passages 16 and 17 lead to a secondary distributing chamber 18 that is parallel to the primary chamber 14.

In order to counteract the effect of the approach velocity of the gas entering the chamber 14 from the inlet conduit 13, the passages 16 that 20 are in line with the conduit 13 are of somewhat smaller cross-section than the passages 17 which are beyond the direct influence of the approach velocity of the entering gas. This obtains more even distribution of the gas to the secondary distributing chamber 18.

30 The end face of the tip 10 has a central portion 20 that is at a different level from side areas 21 of the end face, the central portion 20 being closer to the work than the side areas by a distance of the order of $\frac{1}{2}$ of an inch.

35 Jet passages 22 for the cutting oxygen open through the central portion 20 of the tip and communicate with the secondary distributing chamber 18 through metering ports 23 which are 40 preferably all the same size, and in line with the passages 16, 17.

The jet passages 22 have parallel axes and are 45 preferably disposed in a row. These passages 22 are spaced close enough together so that the oxygen jets that they project against the work cut a common kerf when the torch is moved across the work with the length of the row of passages 22 transverse of the direction of relative movement of the torch across the work.

50 Passages 25 for supplying a mixture of oxygen and fuel gas for preheating flames open through the side areas 21 at spaced points along generally arcuate lines around the ends of the cutting jet passages 22.

55 Oxygen is supplied to the passages 25 through

a port 26 from an annular chamber 27, and fuel gas, such as acetylene, enters the passages 25 from an annular chamber 28 through a port 29.

Figs. 4 and 5 show a modified form of the invention for cutting narrower kerfs than the tip of Figs. 1-3. A tip 30 has the same construction as the tip 10 except that there are fewer passages for both cutting oxygen and preheating flame gas.

Oxygen is supplied from an inlet conduit 33 to 10 a primary distributing chamber 34 that has three passages 36, 37 leading to a secondary distributing chamber 38. Passage 36 is in line with the conduit 33 and is of smaller cross-section than the passages 37 that are far enough to the side 15 not to be affected directly by the approach velocity of the gas entering the chamber from the inlet conduit 33.

Opposite the ends of the passages 36, 37 there are metering ports 38 through which oxygen is 20 supplied to cutting jet passages 40 that open through the end face of the torch. There are only three jet passages 40 in the tip of Figs. 4 and 5 instead of five as in the tip of Figs. 1-3. The three-orifice tip is for cutting narrower kerfs. Because of the shorter row of cutting jet orifices, the tip 30 needs fewer preheating flames. Four preheating jet passages 41 are shown in Fig. 4.

In operating the torch of this invention, the 30 end-face surface through which the cutting jet passages 22 or 40 open is kept within about $\frac{3}{32}$ of an inch of the surface of the work-piece. If the torch is moved further from the work, the 35 parallelity of the side walls of the kerf drops off sharply. The fact that the side areas of the end face are spaced further from the work prevents backfiring of the preheating flames.

When the tip is to be used for cutting kerfs of a width narrower than the length of the row 40

of cutting jet orifices, the tip is turned so that the row extends at an oblique angle to the direction of relative movement of the torch across the work.

Changes and modifications can be made in the illustrated embodiments of the invention, and some features can be used without others.

I claim:

1. A tip having an end face, a plurality of jet passages opening through the end face, a distributing chamber from which gas is supplied to said jet passages, an initial distributing chamber, a plurality of communicating passages between said distributing chambers at points spaced along a line extending transversely of the tip, and a gas inlet conduit opening into the initial distributing chamber on the side opposite the communicating passages, said communicating passages being substantially smaller in cross-section than the inlet conduit and those of the communicating passages directly opposite the gas-inlet conduit being of smaller cross-section than the other communicating passages.

2. A tip having a primary and a secondary distributing chamber, communicating passages between the chambers at points spaced along a line extending transversely of the tip, an inlet conduit opening into the primary distributing chamber on the side opposite the communicating passages, those of the passages directly opposite the inlet conduit being of smaller cross-section than the others of said passages, a plurality of other passages leading from the secondary distributing chamber and opening through an end face of the tip, and metering ports of equal size in each of said other passages and at the upstream end of the passages.

GEORGE L. WALKER.
